DESIGN FOR AN EARRING

Adolph Katz, Providence, R. I., assignor to Coro, Inc., New York, N. Y., a corporation of New York

Application June 5, 1947, Serial No. 139,472

Term of patent 7 years

(Cl. D45—9)

To all whom it may concern:

Be it known that I, Adolph Katz, a citizen of the United States of America, residing in Providence, county of Providence, and State of Rhode Island, have invented a new, original, and ornamental Design for an Earring, of which the following is a specification, reference being had to the accompanying drawing, forming a part thereof.

Fig. 1 is a plan view of an earring, showing my new design.

Fig. 2 is an edge view thereof.

I claim:

The ornamental design for an earring, substantially as shown.

ADOLPH KATZ.
